JULIUS K. LUX, OF ST. LOUIS, MISSOURI.

CONTROLLING MEANS FOR ELECTRIC CIRCUITS.

977,664.

Specification of Letters Patent.

Patented Dec. 6, 1910.

Application filed April 26, 1906. Serial No. 313,836.

To all whom it may concern:

Be it known that I, JULIUS K. LUX, a citizen of the United States, residing at St. Louis, in the State of Missouri, have invented certain new and useful Improvements in Controlling Means for Electric Circuits.

My invention relates to improvements in electric switches, and it consists in the constructions, combinations, and arrangements herein described and claimed.

An object of my invention is to provide an electric switch operating with a minimum of friction, and which is capable of actuation with a quick, snap action with a minimum of shock.

A further object of my invention is to provide an electric switch capable of being brought to a position of efficient contact by a relatively small actuating force, and which shall be durable and inexpensive in construction.

In the accompanying drawings, forming a part of this application and in which similar reference symbols indicate corresponding parts in the several views: Figure 1, illustrates my invention embodied in a double-break snap switch; Fig. 2, is a plan view of the construction shown in Fig. 1, and Fig. 3, is a view similar to Fig. 1, with the switch in open position. Figs. 4 and 5 are detailed views of a portion of the mechanism, partly broken away. Fig. 6 is an elevation of the coil spring showing the housing in section.

Referring to the drawings, A indicates a base, preferably formed of suitable insulating material, and carrying fixed contacts B and C, provided with binding posts B³ and C³ for attaching the ends B², C² of conductors.

A support D, carried by the base A, provides bearings for the several movable elements of the device. Movable contacts G and I are journaled at G³ in the support D, and provided with a bearing for rotatably receiving a trunnion screw M³, which latter is journaled in the bearing D. The screw M³ is provided with threads for engaging a threaded opening in the operating handle E, to rigidly secure said handle thereto.

A spur toothed element L is arranged on the operating means E in operative engagement with a spur gear K. The gear K is secured to a double-crank shaft F, F², F⁴, which crank is journaled at F¹ and F³ in the support D, and constitutes a tensioning

means for a plurality of actuating springs J, J¹.

A plate H, provided with a stiffening flange H⁷, is shown secured to the movable contacts G, I, and provided at its rear portion with an upwardly extending flange G⁵ and with a downwardly extending flange G². The actuating spring J is connected to the crank F² and to the downwardly extending flange G², and the spring J¹ is similarly connected to the crank F⁴ and the upwardly extending flange G⁵.

Fig. 1 shows said connection of the spring J¹ to its flange G⁵ located above the connection of the spring J to its flange G², and also at a less distance from the pivotal support of the movable contact than is such connection of the spring J to its flange G². By this construction, the tension of the spring J¹ decreases more rapidly than that of the spring J during the opening swing of the movable contact, and the tension of the spring J¹ is wholly relieved before the movable contact reaches the end of its opening swing, thus producing a greater aggregate tension or force in closing the switch than in opening the same. This arrangement of the actuating springs enables the spring J¹ to be made sufficiently strong and heavy to insure an efficient closing of the switch, without producing an excessive shock in the opening swing of the movable contact. The frictional engagement of the movable contact with the fixed contacts B and C constitutes a yielding resistance which acts to prevent shock on the closing swing of said movable contact.

The operating handle E is provided with an arm M arranged to engage a portion M² of the movable contact when said handle is operated to open the switch, and to engage the top surface of said movable contact when the handle is operated to close the switch. It will be clear, that upon operating the handle to shift the movable contact, the spur K will be turned to shift the adjustable means F², F⁴, to the desired position, and the arm M will positively engage the movable contact for giving it an initial movement. Suitable stops D⁶, D⁷ are provided for limiting the opening and closing movement of the operating handle E.

A conductor N³ is secured by a binding post N² to a support N⁵, which carries a housing N⁴ for a flexible conductor N of

resilient material similar to that shown in my pending application No. 327,159, filed July 21, 1906.

I have shown the flexible conductor N 5 coiled in the housing N⁴ and having one end secured in electrical circuit with said housing N⁴ and conductor N³. The other end of said coiled conductor is shown extending in the axis of the pivotal support of the movable contact, and having its end portion formed radially for attachment to a binding screw N¹ on said movable contact. This arrangement of the flexible contact obviates frictional rubbing and danger of entanglement thereof during the swing of the movable contact.

The flexible contact can be so arranged that it will be free from stress when the binding screw N¹ is substantially at the mid 20 portion of its travel. This arrangement insures an equal but opposite stress in the coil of the flexible conductor for the two extreme positions of the movable contact, and causes the conductor to constitute a resilient 25 means acting to accelerate the movement of the movable contact during the initial portion of its swing and to retard such movement during the latter portion of its swing; this retarding action during the latter portion 30 of the swing provides a yielding resistance, which acts as a buffer for preventing shock to the moving parts of the device. In such construction, the work exerted by the flexible conductor on the movable contact for accelerating the movement of the latter during the initial portion of its swing is restored in said conductor during the action thereof in retarding the motion of the movable contact in the latter portion of its 35 swing; the algebraic sum of such accelerating and retarding work during a complete swing of the movable contact being equal to zero. The flexible conductor N, thus acts on both swings of the movable contact to 40 accelerate its initial movement and to constitute a yielding buffer at the end of the swing.

The portions m⁸ (and also m⁷) are dead center obviators. When the spring J is at 50 the dead center the stress thereof is non-propulsive and if allowed to remain at that point for a length of time it is, owing to the stress, detrimental to the spring. The said portions m⁷ and m⁸ are formed as flat 55 springs having resilient or yielding movement relatively to M; and in case of a partial movement of the handle E insufficient to carry F beyond the dead center of the spring movement the said portions operate 60 to return the handle E and the conveyer F, to their open or closed positions as the case may be. In other words m⁷ and m⁸ prevent E and F from sticking or dwelling at the dead center of the spring movement. 65 The said portions m⁷ and m⁸ are preferably

made integral; they assist the snap opening and closing of the device respectively; and the latter is more easily compressed than the former.

The part m⁷ yieldingly actuates or accelerates the movable contact during only a part of the snap movement of the latter and the spring J first co-acts with the spring m⁷ and thereafter completes the opening movement unassisted. By this means the 70 movable contact will have no gradual or part opening movement but only a complete snap opening movement. The part m⁷ engages the part M² after a prearranged movement of the operating handle; the 75 former is placed under increasing stress as the part J, nears the dead center, and the parts are so adjusted and proportioned that when m⁷ is fully compressed the energy 80 stored therein starts the co-operative contacts apart with a quick snap movement and preferably irrespective of the opening power 85 of the spring J. The spring J meanwhile is brought into position to co-act with m⁷ and to complete the opening movement. 90 It will be noted however that the yielding part m⁷ could snap the contacts apart and break the circuit. The portions m contact before touching the part M and when the said parts touch their combined yielding 95 powers are applied to M².

Other features are that the power of the spring J to snap the co-operative contacts apart may be decreased so as to reduce the opening shock while not lessening the arc 100 restricting snap movement. Or the yielding means N may be made stronger or less easily compressed so as to decrease the shock incident to the opening movement. Or both of the last two mentioned features may be 105 used to open the device with reduced shock.

From the above description, it will be seen that my invention provides an efficient form of electric switch free from unnecessary strains and operating with a minimum 110 of friction.

I have illustrated and described a preferred and satisfactory construction, but, obviously, changes could be made.

Having thus described my invention, what I claim as new and desire to secure by Letters Patent is:

1. In a device of the character described, co-operative fixed and movable contacts, operating means including yielding means for urging the co-operative contacts together and apart, and a yielding starter impelled by the said operating means to yieldingly urge the said movable contact, during a portion of its movement.

2. In a device of the character described, the combination of fixed and movable contacts, operating means including a yielding starter for initially starting the movable contact from its extreme positions and re-

- silient means carried by said operating means for actuating said movable contact during a portion only of its movement, substantially as described.
- 5 3. In a device of the character described, the combination of fixed and movable contacts, means for actuating said movable contact with a quick, snap action, and a flexible conductor so attached to the movable contact that it will be free from stress at the mid portion of the travel of said movable contact, substantially as described.
- 10 4. In a device of the character described, the combination of fixed and movable contacts, means for actuating said movable contact with a quick, snap action, and a flexible conductor attached to said movable contact and formed to extend in a position equidistant from the two extreme positions of its 20 point of attachment to said movable contact, whereby said flexible conductor acts on both the opening and closing movements of the movable contact to accelerate the movement during one portion of the travel of the 25 movable contact and to retard the movement during another portion of such travel, substantially as described.
- 30 5. In a device of the character described, the combination of fixed and movable contacts, yielding means for actuating said movable contacts with a quick, snap action, and a flexible conductor secured to said movable contact for augmenting the force of 35 said yielding means during the initial portion of the movement of the movable contact and opposing the action of said yielding means during the latter portion of the movement of said movable contact, substantially as described.
- 40 6. In a device of the character described, the combination of fixed and movable contacts, means including a yielding starter for actuating said movable contact with a quick, snap action, and resilient means constituting a yielding buffer for absorbing shock 45 on the opening and closing movement of said movable contact, substantially as described.
- 50 7. In a device of the character described, the combination of fixed and movable contacts, a pivotal support for said movable contact, yielding actuating means for swinging said movable contact on its pivotal support with a quick, snap action, and a flexible conductor attached to said movable contact at a distance from said pivotal support, and formed to bring its axis in line with the axis 55 of the pivotal support, substantially as described.
- 60 8. In a device of the character described, the combination of fixed and movable contacts, a pivotal support for said movable contact, actuating means for swinging said movable contact on its pivotal support with a quick, snap action, and a flexible conductor 65 of resilient material connected to said movable contact for augmenting the force of said actuating means during the initial portion of the opening and closing swings of the movable contact, substantially as described. 70
9. In a device of the character described, the combination of fixed and movable contacts, a pivotal support for said movable contact, actuating means for swinging said movable contact on its pivotal support with a quick, snap action, and a flexible conductor of resilient material connected to said movable contact to augment the force of 75 said actuating means during the initial portion of the swing of the movable contact and to constitute a yielding buffer for said movable contact during the latter portion of its swing, substantially as described. 80
10. In a device of the character described, the combination of fixed and movable contacts, a pivotal support for said movable contact, operating means constructed to engage said movable contact in its extreme positions for shifting the latter therefrom, and a flexible conductor of resilient material 85 connected to said movable contact to augment the action of said operating means during the initial portion of the swing of the movable contact and to constitute a yielding buffer for said movable contact during the latter portion of its swing, substantially as described. 90
11. In a device of the character described, the combination of fixed and movable contacts, a pivotal support for said movable contact, yielding actuating means for swinging said movable contact on its pivotal support with a quick, snap action, operating means constructed to engage said movable 95 contact in its extreme positions for shifting the latter therefrom, and a flexible conductor of resilient material connected to the movable contact for accelerating the movement of said movable contact during the 100 initial portion of its swing and retarding such movement during the latter portion of its swing, substantially as described. 105
12. In a device of the character described, the combination of fixed and movable contacts, a pivotal support for said movable contact, yielding actuating means including a yielding starter for swinging said movable contact on its pivotal support with a quick, snap action, and resilient means for accelerating the movement of said movable contact during a portion of its swing and retarding such movement during another portion 110 of its swing, substantially as described. 115
13. In a device of the character described, the combination of fixed and movable contacts, a plurality of actuating springs for actuating said movable contact, and means for tensioning said several springs to produce a greater aggregate tension therein. 125 120 130

during the closing movement of the contact than in the opening movement thereof, substantially as described.

14. In a device of the character described, 5 the combination of fixed and movable contacts, a pivotal support for said movable contact, yielding actuating means for swinging said movable contact on its pivotal support, and resilient means connected to said 10 movable contact to augment the force of said actuating means during the initial portion of the swing of the movable contact and to constitute a yielding buffer for said movable contact during the latter portion of its 15 swing, said parts being positioned to exert a greater force on the movable contact during its swing to closed position than on its swing to open position; substantially as described.
16. In a device of the character described, 20 the combination of fixed and movable contacts, a pivotal support for said movable contact, a plurality of actuating springs for swinging said movable contact on its pivotal support, means for tensioning said plurality of springs to bring all of said springs into action during the entire swing of the movable contact to closed position and to maintain only a portion of said springs in 25 action during the complete swing of the movable contact to open position, substantially as described.

17. In a device of the character described, 30 the combination of fixed and movable contacts, a pivotal support for said movable contact, a movable spring actuator, a plurality of actuating springs connected to the said movable contact and actuator, and operating means for moving said actuator to 35 bring all of said springs into action during the entire swing of the movable contact to closed position and to maintain only a portion of said springs in action during the complete swing of the movable contact to 40 open position, substantially as described.

18. In a device of the character described, 45 the combination of fixed and movable contacts, a pivotal support for said movable contact, a housing arranged axially to said 50 pivotal support, and a coiled flexible conductor within said housing and connected to said movable contact, substantially as described.

19. In a controlling means for electric circuits, a support, an electrical contact carried thereby, a coöperative movable contact, and means for operating the same, said means comprising an element for yieldingly actuating the movable contact during a predetermined movement thereof, and an element for yieldingly actuating said movable contact during only a portion of such predetermined movement.
20. In a controlling means for electric circuits, a support, an electrical contact carried thereby, a coöperative movable contact, and means for operating the same, said means comprising an element for yieldingly actuating the movable contact during a predetermined movement thereof, and an element impelled by the said operating means for yieldingly actuating the said movable contact through a portion of such predetermined movement.

21. In a circuit controlling device, a suitable support, an electrical contact carried thereby, a movable contact adapted to coöperate with the first-mentioned contact, yielding actuating means permanently connected with the said movable contact, energizing means with which the said yielding actuating means is also permanently connected, said yieldingly connected parts having relative movement whereby the coöperative contacts are urged together and apart with quick snap actions, and yielding means intermittively connecting the said energizing means with the said movable contact and accelerating the initial portion of the movement of the latter.

22. In a circuit controlling device, a suitable support, an electrical contact carried thereby, a movable contact adapted to coöperate with the first-mentioned contact, yielding actuating means operatively connected with the said movable contact, energizing means with which the said yielding actuating means is also operatively connected, said yieldingly connected parts having a movement whereby the coöperative contacts are urged together and apart with quick snap actions, and yielding means initially urging the coöperative contacts apart during a pre-arranged portion of the opening movement thereof.

23. In a circuit controlling device, a suitable support, an electrical contact carried thereby, a movable contact adapted to coöperate with the first-mentioned contact, yielding actuating means operatively connected with the said movable contact, energizing means with which the said yielding actuating means is also operatively connected, said yieldingly connected parts having a relative movement whereby the coöperative contacts are urged together and apart with quick snap actions, and supplemental yielding

means initially urging the coöperative contacts apart during a pre-determined portion of the opening movement.

24. In a circuit controlling device, a suitable support, an electrical contact carried thereby, a movable contact adapted to coöperate with the first-mentioned contact, a plurality of yielding actuating means permanently connected with the said movable contact, energizing means with which the said yielding actuating means is also permanently connected, said yieldingly connected parts having relative movement whereby the coöperative contacts are urged together and apart with quick snap actions, and yielding means intermittively urging the movable contact so that a pre-arranged plurality of said yielding actuating means initially accelerate the movable contact and less than the said plurality of yielding means accelerate the movable contact during succeeding stages of its movement.
25. In a circuit controlling device, a suitable support, an electrical contact carried

thereby, a rocking contact adapted to coöperate with the first-mentioned contact, yielding actuating means operatively connected with the said rocking contact, energizing or tensioning means with which the said yielding actuating means is also operatively connected, said yielding connections effecting a movement with greater yielding stress at the dead center than in the closed position of the device to urge the coöperative contacts together and apart with quick snap actions, and supplemental yielding means urging the said tensioning means away from the dead center of the opening movement and toward the normal closed position of such tensioning means whereby the parts are prevented from dwelling near the dead-center of the spring movement.

April 26, 1906.
